GAME BOARD

John Scarne, Fairview, N. J.

Application July 22, 1947, Serial No. 140,442

Term of patent 14 years

(Cl. D34—5)

To all whom it may concern:

Be it known that I, John Scarne, a citizen of the United States of America, residing in the city of Fairview, county of Bergen, and State of New Jersey, have invented a new, original, and ornamental Design for a Game Board, of which the following is a specification, reference being had to the accompanying drawing, forming a part thereof:

The figure is a view in perspective of a game board showing my new design.

The hatching which shows in the circles of the figure is intended to represent color areas.

The dominant features of my design are shown in the solid lines in the drawings.

I claim:

The ornamental design for a game board, as shown and described.

JOHN SCARNE.
